UNITED STATES PATENT OFFICE.

SHERWOOD C. BLISS, OF KENMORE, NEW YORK, ASSIGNOR TO AMERICAN RADIATOR COMPANY, OF NEW YORK, N. Y., A CORPORATION OF NEW JERSEY.

MOLD-RAMMING MACHINE.

Application filed April 14, 1924. Serial No. 706,270.

My invention relates to new and useful improvements in mold-ramming machines, and has for its primary object to provide an improved and highly efficient machine for properly ramming molding sand, or equivalent material, in a flask or mold, so that such material will properly conform to any desired pattern or form which may be employed to determine the shape or configuration of the product to be made or cast in the mold.

A further object is to provide an improved, efficient and simplified means for propelling the ramming machine embodying my invention relative to the flask or mold upon which the ramming operation is to be performed.

A further object is to provide an improved and simplified means for automatically controlling the travel of the ramming machine relative to a flask or mold.

20 A further object is to provide simple and efficient means for reversing the travel of the ramming machine should the same encounter an unintentional obstruction during the travel of the machine.

25 A further object is to provide a ramming machine which will have efficient means for distributing the sand in the mold so that the same will be properly distributed when acted upon by the ramming means.

30 While I have stated above certain objects which the invention seeks to accomplish, other objects and advantages of the machine will be apparent from the detailed description hereinafter given.

35 The invention consists in the improved construction and combination of parts and mechanism, to be more fully described hereinafter, and the novelty of which will be particularly pointed out and distinctly claimed.

40 In the accompanying drawings, to be taken as a part of this specification, I have illustrated a preferred embodiment of my present invention, and in which—

Figure 1 is a top plan view of the invention, 45 certain of the parts being broken away for the sake of clearness;

Fig. 2 is a view in side elevation of the embodiment shown in Fig. 1, certain of the parts being broken away, and others being in section, the machine being shown in its starting position;

50 Fig. 3 is a view in front elevation of the structure shown in Figs. 1 and 2, certain of the parts being in partial section, and parts 55 of the safety stop and motor control mecha-

nisms, which constitute parts of the invention, being omitted;

Fig. 4 is a section on line 4—4 of Fig. 3, parts of the safety stop and motor control mechanisms being omitted;

60 Fig. 5 is a view in front elevation of the structure shown in Figs. 1 and 2, the buffer-plate forming one of the elements of a safety stop mechanism, and parts of the ramming mechanism, being omitted;

65 Fig. 6 is a view in side elevation showing a mechanism for controlling the travel of the ramming machine, and showing the parts in the position assumed at the moment the direction of travel of the ramming machine is 70 reversed during normal operation;

Fig. 7 is a detail view in side elevation of the controlling mechanism shown in Fig. 6, and showing the parts in the position assumed thereby when in normal position and 75 the ramming machine is travelling forward to pass over a mold to be rammed;

Fig. 8 is a detail view in side elevation of the safety control means shown in Fig. 6, but showing the parts in the position assumed 80 when the direction of travel of the ramming machine is reversed because of the buffer-plate on the safety stop mechanism meeting with an obstruction.

Fig. 9 is a detail perspective view of certain 85 elements of the controlling mechanism shown in Figs. 5, 6, 7 and 8;

Fig. 10 is an enlarged detail perspective view of a structure, including means for distributing the sand in a mold, and also for preventing the sand being thrown therefrom 90 while the ramming operation is in progress;

Fig. 11 is a detail perspective view of certain elements of the sand-distributing means illustrated in dotted lines in Fig. 10;

Fig. 12 is a detail view of a portion of the stop mechanism for arresting travel of the carriage at the end of a reciprocation, and

Fig. 13 is a detail view of one of the ramming elements showing the same in another 100 position of adjustment.

Referring to the drawings, particularly Fig. 2, by characters of reference, A designates a pattern support of any suitable type, and which is adapted to support upon its upper portion a pattern (not shown), and a mold or flask B adapted to receive molding sand, or its equivalent, which is adapted to conform to the pattern. These elements may be of any suitable or well-known construction, and in- 105

asmuch as the same are not of my present invention, it is not believed necessary to show or describe the same in greater detail.

1, 1 designate longitudinal members of a suitable trackway adapted to support a carriage upon which the ramming element or elements are mounted, and along which trackway said carriage is adapted to travel in order to cause the ramming means to traverse a mold containing molding sand which is to be rammed to conform to a pattern. The members 1, 1, composing this trackway, may take a number of forms within the spirit of this invention, but are preferably in the form of channel-irons or beams supported rigidly, in any suitable manner, on overhead girders 1^a, with central or intermediate webs 2 of said channel-irons in parallel vertical planes, and with their lateral or edge flanges 3 preferably directed outward, as clearly shown in Figs. 3 and 5 of the drawings. The inner lower edges of the members 1, 1 are provided with longitudinally extending angle-irons 4 having a vertical flange 5 riveted to the web 2, and also having a horizontal flange 6 serving as a support for longitudinally extending track rails 7, which are preferably in the form of T-rails, as clearly shown in Figs. 3 and 5. These rails 7 are rigidly secured to flanges 6, in any suitable manner (not shown), extend parallel to each other, and constitute a bed or support for the hangers of a carriage, which will now be described.

The rammer carriage preferably comprises an upper frame member which, in general, is rectangular in plan view (see Fig. 1), including longitudinally extending side members 8, 8, which are connected, braced and stiffened by transverse end members 9, 9, and web members 10 aligned in a horizontal plane. It will be noted that the construction just described provides a horizontally disposed rectangular frame having a central opening 11, which serves a purpose to be presently described. This frame member is preferably, but not necessarily, cast in an integral structure.

At its opposite ends, and at each side thereof, the frame member just described is provided with an upwardly extending hanger or bracket 12, which is rigidly secured by bolts 13, or other means, to the transverse end member 9 of the frame. Each of these brackets includes an upwardly extending arm 12^a provided at its upper end with an apertured boss 14, in which is suitably fixed a bearing pin or journal 15. The bearing pin 15 in each instance projects outward over the adjacent track rail 7 and carries a bearing or running roller 16 adapted to rest and travel on the tread of said track rail. These brackets or hangers, and running rollers, just described, support or suspend the rammer carriage from the trackway, and permit it to travel along the same. In order to pro-

vide for smooth travel of the carriage on its trackway, each of the brackets 12 is provided with an arm 17 carrying a boss 18, in which is secured a vertically extending bearing pin 19, upon which is journalled a guiding and holding roller 20 arranged to travel on the inner side face of the adjacent track rail, and thus serve to hold the rollers 16 in proper running engagement with the trackway during the traversing movement of the carriage. Rigidly connected to the corner portion of the upper frame member heretofore described, are depending vertical corner members 21, which are connected at their upper ends by means of suitable bolts 22 to said carriage frame member, said members 21 preferably, but not necessarily, consisting of angle-irons arranged with their flanges 21^a at right angles to each other. The corner members 21 are connected at their lower side portions by upper and lower parallel bracing members 22, 23, respectively, which are connected to the side flanges of the members 21 by means of angle brackets 24 and suitable bolts or rivets 25. The frame members may also be braced by means of cross members 26 having their ends bolted, respectively, as at 27, to the side flanges of the members 21. The frame members 21 are braced transversely relative to each other by certain elements to be described hereinafter.

I will now proceed to describe a ramming means carried by the carriage above described.

On the forward lower portion of the side members 8, 8 of the carriage frame are provided alining bearing-boxes 28, in which is arranged a horizontal crank-shaft 29 extending transversely of the carriage, and provided with an inner pair of cranks 30 extending in the same direction from the crank-shaft center, and outer cranks 31 arranged between the cranks 30 and the boxes 28 and extending in opposite directions to the said cranks 30, as clearly shown in Figs. 3 and 4 of the drawings. The central portion of the crank-shaft 29, between the said inner cranks 30, is journaled in suitable bearing-boxes 32 supported rigidly, in any suitable manner, from the lower portion of the carriage frame member. Upon each of the cranks 30, 31 is arranged a bearing-box 33, of any suitable construction, and from each of which is suspended a depending connecting rod 34, in the present embodiment there being four of such rods, as will be apparent upon reference to Fig. 3 of the drawings. The lower ends of the inner pair of connecting rods 34 are apertured, as at 35, to receive and support the outer ends of a cross shaft 36, from which is suspended a ramming element or elements adapted to be vertically reciprocated when the shaft 29 is rotated, as will be hereinafter described. The lower ends of the outer pair of depending rods 34 are each fixed, as at 37, 130

to a bearing-pin 38, guided in apertures 39 in ears 40 on the outer ends of reach or spacing bars 41, the opposite ends of which are apertured and pivoted, as at 41^a between 5 adjustable collars 41^b, adapted to be fixed by screws 41^c on a transverse shaft or rod 42, supported rigidly by the rear frame members 21, in any suitable manner. The shaft 36 is likewise connected by means of spacing or dis- 10 tance rods 43 to said shaft 42, whereby the vertical movement of the lower ends of the said rods 34 is controlled to take a definite path.

I will now proceed to describe the ramming 15 element adapted to be operated by the reciprocations of the rods 34, reference being particularly had to Figs. 3 and 4 of the drawings:

In the present embodiment, I have shown 20 two ramming elements suspended from the shaft 36 to be operated by the inner pair of rods 34, although it will be understood that one, or more than two elements might be employed, according to the desired capacity 25 of the machine, and one of said elements operated by each of the outer rods 34. In the preferred form, each of these ramming elements comprises a hanger 44 receiving the shaft 36, or the pin 38, as the case may be, 30 and provided with a hollow sleeve or cylinder 45, in which is slidably arranged a shank or plunger bar 46 carrying on its lower end a flange member 47 provided with a suitable ramming foot 48, of any suitable configuration, and which is adapted to engage the sand. The plunger bar 46 is preferably tubular, as at 49, and receives a compression spring 50 abutting the upper end of the sleeve member 45 and the upper end of the ramming foot 48, to cushion the latter, and also urge it outward 35 toward ramming position. The outward movement of the ramming foot, under influence of the spring 50, is limited by stud bolts 51 threaded into the ramming foot, as at 45 52, and extending through openings 53 in ears 54 on the sleeve member 45, the upper ends of said bolts being provided on the upper sides of said ears with nuts 55, and co-operating with said ears to limit movement of 50 the foot outward, but permit inward movement against the spring 50. If desired, cushion blocks or washers 56 of rubber, or other suitable material, may be arranged between the nuts 55 and the ears 54.

I will now describe a preferred means for 55 guiding the lower ends of the connecting rods during reciprocation, so as to assure the ramming foot operating in proper alignment: The carriage with the rammers is adapted to 60 be propelled, by means to be presently described, to pass with continuous movement across the face of the mold, and during this movement the rammers are continuously reciprocated vertically, by means to be presently described. It will be seen that if the ram-

mers are continuously operated during the period of travel of the carriage, there will be times during which one or the other pair of rammers will be in its lower position in contact with the molding sand, which would 70 mean that the carriage would drag the lowermost rammer through the sand, thereby disturbing and pushing the sand ahead of it. In order to prevent this result, I employ 75 means whereby the rammer feet, in lower position and in contact with the sand, will not be moved forward with the carriage, but will leave the sand by substantially vertical movement from the lowermost point reached in ramming the sand. The result stated is ac- 80 complished by providing improved means whereby during the travel of the carriage the rammer feet, when driven downward to ram the sand, will be permitted to remain in initial place of contact until the connecting rod 34 85 operates to lift the feet from the sand. This means (see Figs. 2 and 4), comprises pairs of extensible yielding links, each of which is preferably in the form of a rod 57 having one end pivoted, as at 58, to the element 45, the opposite end portion of each of said rods being slidably arranged in guide openings in bosses 59 on a swinging bracket 60, having one end pivoted, as at 60^a, on a transverse rod 61 rigidly mounted on the carriage frame, for example, by shackles 62. Rigid with each rod 57 between the bosses 59 is a stop-collar 63, on opposite sides of which, and between the same and said bosses, are arranged coiled springs 64, 65, respectively. The arrangement and 90 construction is such that when the carriage is travelling forward, for example, toward the left of Figs. 2 and 4, and one of the pairs of rammer feet is in contact with the sand, such pair will not be moved forward with the 95 carriage while in such contact, but will momentarily remain stationary, the lower end of the connecting rod 34 swinging forward on the shaft 36, or the pin 38, as the case may be, and the rod 57 sliding rearward through 100 the bosses 59 and compressing the spring 65. As soon as the cranks 30 or 31 have moved far enough to lift the rammer foot clear of the sand, the spring 65 will expand and throw the foot forward into position to be moved 105 downward again to ram the sand. It will be seen that the extensible links 57 described, provide the necessary relative movement between the carriage and the rammers, which 110 will permit the latter to remain stationary in contact with the sand until the cranks lift the rammers in a substantially vertical direction out of the sand. When the carriage travels rearward, that is, toward the right of Fig. 2, the carriage pulls the bosses 59 against the 115 spring 64, compressing the same against the collar 63, the rammer foot remaining stationary in contact with the sand. When the crank lifts the foot, the spring 64 exerts its force 120 against the collar 63 to pull the foot into po- 125 130

sition to again be moved downward by the crank, the operation being the reverse of that described as taking place when the carriage is travelling forward.

5 I will now describe a novel means for propelling the carriage across the face of a mold in order that the ramming means will ram the sand, and for controlling such propulsion: This means comprises a flexible element, preferably in the form of a cable 66, one end of which is suitably anchored at a point off the carriage, for example, to a transverse member 67 supported by the trackway structure 1. The connection or anchorage for the cable is 10 afforded, preferably, by providing one of the ends of the cable with a socket coupling piece 68 which is pivotally connected, as at 69, to a rod 70, slidably extending through an opening in the member 67, and through a 15 guide opening in an angle-bracket 71 rigidly supported on the member 67. The outer end of the rod 70 extends beyond the member 67, and is provided with a stop-washer 72, adjustably held in position by nuts 73 threaded 20 onto the end of said rod, and between said washer and the member 67 is arranged a cushion block 74, for example, of rubber, to resiliently resist pull on the cable 66.

The opposite end of the cable from that 25 just described, is also connected or anchored to a point off the carriage and to the opposite end thereof from the anchorage heretofore described. The anchorage for this latter end of the cable may also consist of a socket coupling member 75, pinned, as at 76, to a rod 77 extending through an opening in a transverse member 78 supported by the track members 1. In this case the rod slidably extends 30 through an opening in the member 78 and a bracket 79, and is provided at its outer end with a stop-washer 80, adjustably held in position by nuts 81 threaded onto said rod. In this case I may also employ a cushion member between the stop-collar or washer 80 and 35 the member 78, for example, an expansion spring 82. The intermediate portion of the cable 66 is looped or wound about a drum 83 having a spiral groove thereon to receive and guide said cable, the latter being connected 40 to the drum by a suitable anchorage block 84 overlying a turn of the cable and bolted to the drum, as shown, the arrangement of the cable being such that the opposite end portions thereof pass from the upper portion of the 45 drum and in opposite directions from each other toward the ends of the trackway, as will be apparent from Figs. 1, 2 and 4 of the drawings. The drum is driven by any suitable means, but I preferably provide a 50 reversible electric motor 85, of any suitable type, which is suspended by hanger brackets 86, bolted, as at 87, to the underside of the upper frame member of the carriage. (See Fig. 6.)

The armature shaft 88 of the motor is provided with a driving pinion 89, which meshes

with a gear 90 fixed on a shaft 91 mounted in suitable bearing hangers 92, shown in dotted lines in Fig. 4, also supported from the underside of the top frame member. The shaft 91 has fixed thereto a pinion 93 (shown in dotted 70 lines in Fig. 4), which meshes with a gear 94 fixed to a shaft 95 mounted in suitable boxes 96 on the carriage frame, and which shaft 95 carries a fixed pinion 97 meshing with a gear 98 on the shaft 83^a of the drum 83. By the 75 arrangement just described, the drum 83 may be driven in either direction, according to the direction of rotation of the reversible motor. When the motor is turned in one direction, it will drive the drum to take up one end portion of the cable 66, for example, that extending to the left of Fig. 1, and will pay out the other end portion of the cable which extends to the right of Fig. 1, thus serving to drive the carriage forward, or toward the left 80 of Fig. 1. When the drum is driven in the opposite direction, it takes up the end portion of the cable 66 to the right of Fig. 1, and pays out that portion of the cable extending to the left of Fig. 1, thereby driving the carriage toward the right of Fig. 1. The motor 85, heretofore described, also serves as the driving means for the rammer-operating shaft 29, this being accomplished by providing 85 a gear 99 on that portion of the shaft 29 which is located between the bearing-boxes 32, as shown in Fig. 3, which gear 99 is arranged in mesh with the forward portion of the gear 90 heretofore described. It will thus be seen that when the motor is operated to take up 90 and pay out the cable 66 to propel or reciprocate the carriage, that the rammers will also be reciprocated to perform the ramming operation on the mold, the propulsion of the carriage and the driving of the rammers taking 95 place simultaneously.

I will now describe the control means for controlling the propulsion of the carriage and the driving of the ramming means: This control means preferably consists of a circuit-controller 100, which may be, and preferably is, of any suitable commercial type which is capable of controlling the current to the motor 85 to drive the latter in either direction, and also which will have a neutral position at 100 which the armature of the motor will be at rest, the current to the motor being cut off. The controller 100 is preferably mounted on a bracket 101, supported on the front portion of the upper carriage member, said controller including a shaft 102 which carries contacts (not shown) cooperating with fixed contacts within the controller casing for effecting the method of control just mentioned. The casing of the controller is connected by a conduit 103 with a conduit box 104, to which leads an inlet conduit 105 containing the inlet leads 106 from a suitable source of current, and which pass through the conduit 105, conduit box 104 and conduit 103 to the controller. 105

- The outlet leads from the controller pass through the conduit 103, the conduit box 104 and an outlet conduit 107 to the motor, entering the same through a suitable inlet opening 108, in the motor casing. For the sake of clearness, the circuit leads to the motor have been omitted, but the arrangement will be perfectly clear from the above description taken in connection with the drawings.
- 10 Upon the shaft 102 of the controller is fixed a gear segment 109, with which meshes a gear segment 110 fixed to a shaft 111 which has bearing in brackets 112, bolted, as at 113, on the upper side of the upper frame member 15 of the carriage. Also mounted upon the shaft 111 is a rocker-arm 114, to which is pivotally connected, as at 115, the upper end of a connecting rod 116, the lower end of which is pivotally connected, as at 117, to a 20 rocker-arm 118, which is fixed to an operating shaft 119, which is mounted to rock in bearing ears 120 on the upper ends of bracket-members 121, the latter being rigidly bolted, as at 122, to the forward side members 21 of 25 the carriage frame. The shaft 119 is provided, preferably on each of its ends, with a suitable operating lever 123, by means of which said shaft may be rocked to throw the segment 110 to thereby operate the controller 30 shaft to either of the circuit-controlling positions, that is, to neutral, or to drive the motor in either of the desired directions. The operating handle or lever 123 is shown in the neutral position in Fig. 2; in Fig. 7 35 in the position in which the motor is driven to cause the cable 66 to pull the carriage forward, and in Figs. 6 and 8 in the position in which the controller is operated to cause the motor to operate in the reverse direction 40 to thereby reverse the pull on the cable and reverse the direction of travel of the carriage. It will be apparent that when it is desired to control the carriage manually, it is only necessary to move the controlling lever 123 45 to any one of the positions just described.
- My invention, in its preferred embodiment, also contemplates a system of control whereby a controller, for example, the controller 100, may be operated manually to start the carriage from a fixed position to cause the carriage to travel in one direction for a desired 50 distance, and to thereupon have its direction of travel reversed and be returned to the initial position and stopped. This means, in its preferred form, comprises a novel mechanism mounted on the trackway and with which mechanism on the carriage cooperates to effect the sequence of operations mentioned. For the purpose stated the shaft 111 is provided 55 on one end portion with a rocker-arm 124 fixed to said shaft, and carrying on its outer end a contact roller 125. This roller, when the carriage is at its starting point at one end of the trackway, is in the position shown 60 in dotted lines in Fig. 2 of the drawings, and when the lever 123 is moved by the operator from the position shown in Fig. 2 to that shown in Fig. 7, the controller is operated to throw the current onto the motor to drive the latter forward, and the shaft 111 is rocked 65 to elevate the arm 124 to bring the roller 125 to the position shown in Fig. 7. The carriage then moves forward for the desired distance until the roller 125 engages a fixed abutment 126 mounted on a bracket 127 bolted rigidly, 70 as at 128, on one of the side members 1 of the trackway. (See Figs. 1 and 2.) When the roller 125 strikes the end of the stop-bar 126, as indicated in dotted lines in Fig. 6, accompanied by the legend "Ahead", the movement 75 of the carriage causes the said roller and the arm 124 to be moved rearward and downward to the position indicated in dotted lines in Fig. 6 by the legend "Neutral", under which condition current to the motor is cut off, but 80 the inertia or momentum of the carriage continues the travel thereof far enough until the roller 125 strikes an inclined contact face 129 which serves to move the roller 125 and the arm 124 to the position shown in full lines 85 in Fig. 6 and in Fig. 8, in which the roller is beneath a horizontal surface 129^a, which movement rocks the shaft 111 to move the controller rotor to the position reversing the current to the motor to cause the latter to 90 drive in the opposite direction, and thereby propel the carriage in the return or reverse direction and toward its starting point.
- Also rigidly mounted on the shaft 111 is a rocker-arm 130 disposed at an angle to the 100 arm 124, and carrying at its outer end a roller 131, which is adapted to cooperate with suitable means on the trackway to thereby operate the controller to neutral position to stop the carriage when it is returned to its initial 105 or starting point. The means just mentioned for this purpose consists of a bar 132 (see Figs. 1, 2, 5 and 12), rigidly supported at one end on a bracket 133, mounted and secured, as at 134, on one of the side members 110 1 of the trackway, said bar including a lower horizontal portion 135, an intermediate inclined portion 136 and an upper horizontal portion 137, the latter portion extending from the carriage starting point toward the opposite end of the trackway. The opposite end of the bar 132 is preferably supported rigidly by a bracket 133^a connected to the trackway, as at 133^b. The bar portion 137 is provided with a one-way tappet 138 pivoted on 115 a pin 139 let through any desired one of a series of apertures 140 in the said bar portion 137, whereby the position of the tappet may be adjusted longitudinally of said bar. The tappet is provided with a depending engaging lug 141 and with a stop-lug 142, the latter being so arranged that the tappet may swing freely in the forward direction of the carriage travel, but the lug 142 engages with 120 the underside of the bar portion 137 to pre- 130

vent swinging movement of the tappet in the rearward direction to thereby cause the tappet to assume a rigid position when said lug engages said bar, as shown in Fig. 12. 5 When the direction of travel of the carriage is reversed, the arm 130 is swung to the position shown in Figs. 6 and 8, which position is maintained during the reverse travel of the carriage until the roller 131 engages 10 the lug 141 on the tappet 138, at which instant the movement of the carriage causes said roller and the arm 130 to be moved to a lower position where the roller clears the face 136, and finally to take position under the 15 horizontal portion 135, as indicated in dotted lines in Fig. 2. By this operation the controller shaft 102 is rocked to turn the controller rotor to neutral position to shut off current to the motor, whereby the propulsion 20 of the carriage and the driving of the rammers is stopped. When the motor is stopped, as just described, the carriage engages suitable cushion buffers 143 fixed to the trackway adjacent the end of the latter. (See Figs. 1 25 and 2.) Similar stops or abutments, indicated at 144, are arranged at the opposite end of the trackway. Each stop comprises a plunger head 145 (see Fig. 2), slidably disposed within a cylinder 146, said block being 30 provided with an integral extension rod 147 extending through the abutment, as at 148, suitable cushion members 149 being arranged between the rear of the block 145 and the end of the said chamber. When the carriage is 35 brought to the starting point and is stopped, as just described, the operating lever 123 will be brought automatically to the neutral point, from which it may be again operated to cause the carriage to travel in the forward direction of its reciprocation. 40

I also contemplate the provision of means whereby the reversal of travel of the carriage may be effected automatically when the carriage is on the forward movement of its reciprocation and will be reversed, in the event the carriage should meet with an obstruction, for example, a workman, or truck, which may be accidentally or inadvertently in the path of travel. This means comprises a buffer-member adapted to strike the obstruction, and through suitable mechanism operating to effect the shifting of the controller shaft 102 to control the travel of the carriage which mechanism will now be described: 45

50 The brackets 121 on the forward portion of the carriage are each provided at its lower portion with a bearing-eye 150, in which is mounted a shaft 151 arranged parallel to the shaft 119, heretofore described, and on the shaft 119 and said shaft 151 are arranged pairs of upper and lower levers 152, 153, said levers being loosely mounted on upper and lower horizontal parallel rods 154, the ends of which are connected pivotally, as at 55 155, to vertical distance or spacing members

156, whereby a parallel lever motion is provided, that is, the levers 152, 153 may fulcrum or swing on the shafts 119, 151, but said levers and the members 156 are at all times maintained in parallelism, as will be 70 clear from Figs. 2, 5, 6, 7 and 8 of the drawings. The bars 156 also serve as supports for a vertical buffer-member 157, which may consist of a plate connected by bolts 158 to the said members 156. It will be seen that should the buffer-plate encounter an obstruction during the travel of the carriage, said plate will be moved toward the carriage from the positions shown in Figs. 2, 6 and 7 toward that shown in Fig. 8. Loosely mounted on 80 the shaft 119 is a lever 159 to which is connected, as at 160, one end of a contractile spring 161, the opposite end of which is anchored by any suitable means, as at 162, to a bracket 162^a on one of the frame members 85 21. This spring 161 is normally extended and tends to pull the lever 159 from the position shown in Fig. 7 toward that shown in Fig. 8, the spring being restrained against such action during the normal travel of the carriage by a trip arrangement which will now be described: 90

Pivotedly mounted, as at 163, on the upper rod 154, is a floating link 164 having in its free end a longitudinal slot 165 which receives 95 a movable fulcrum pin 166 carried by the lower end of a lever 167, the upper end of which is pivoted, as at 168, to the lower end of a lever 169, the upper end of which is fulcrumed, as at 170, on the frame member 21. 100 The lever 169 is provided with an extension lug 171 carrying an adjustable abutment screw 172 adapted to cooperate with a lug 173 on the lever 167 to limit the swinging movement of the levers 167 and 169 relative to each other in one direction, as will be obvious from Fig. 7 of the drawings. The lever 167 is pivoted at an intermediate point, as at 174, on the lever 159. The lever 159 is provided on its hub mounted on the shaft 119 with an abutment face 159^a extending radially from said shaft and adapted to cooperate with a radial abutment face 159^b on a stop-piece 159^c carried by a hub 159^d, which is rigidly mounted on the shaft to turn therewith, for a purpose 110 115 to be presently described: 115

The hub of each of the levers 152, 153 is provided with a rearwardly extending arm 175, the upper and lower of said arms being each connected by a connecting bar 176. Each 120 of the arms 175 on the upper shaft 119 is provided with a stop-member 177, having a forward abutment face 178 extending radially of the said shaft 119 and adapted to engage with a cooperating face 179 on an abutment 180 125 which is fixed rigidly to the said shaft 119 to rock therewith, the faces 179 on abutments 180 being in alinement with face 159^b on abutment 159^c.

When the carriage is travelling in the for- 130

ward direction, the elements composing the manual control, and the safety reversing mechanism, are in the position illustrated in Fig. 7, at which time abutment faces 159^a and 178 take a position adjacent to but spaced from faces 159^b and 179, respectively, a slight distance, as shown in this figure. The buffer-plate is maintained in the position shown in Fig. 7 by the reaction of pin 166 in lever 167 against the end of slot 165 in link 164, which in turn acts against rod 154 and holds the buffer-plate 157 in its forward position. When the reversal of the carriage takes place upon engagement of the roller 125 with the element 127, the rod 116 is moved upward, thereby rotating the shaft 119 to swing the hand-lever 123 toward the right of Fig. 7, but this movement does not alter the position of the safety stop device, the elements 159^c and 180 merely turning with the shaft 119 so that the faces thereon are moved a further distance away from the surfaces 159^a and 178 heretofore described, as shown in Fig. 6. It will also be seen that by the construction and arrangement just described, the handle 123 can be manually moved to any of its control positions without changing the positions of the safety stop elements. If the parts are in the position shown in Fig. 7, and an obstruction is struck by the buffer-plate, the latter will be moved toward the frame, which will thrust the link 164 inward and cause the inner end of the slot 165 to engage the pin 166, thereby swinging the lever 167 on its fulcrum 174 and moving the connection 168 outward, or to the left of Fig. 7, until the pivotal center of the connection 168 is moved beyond a straight line extending through the centers of the pivots 170 and 174, whereupon the spring 161 will be free to contract, pulling the lever 159 upward and causing the lever system to be moved with a snap action to the position shown in Fig. 8. This operation moves the lever 159 to the position shown in Fig. 8, thereby throwing face 159^b into engagement with the element 159^c, and at the same time the faces 178 come into engagement with the faces 179, due to weight of the buffer-plate, thereby rotating the shaft 119 to throw the lever 123 to reverse position, as shown in Fig. 8. When the levers 167 and 169 are thrown to the position shown in Fig. 8, the buffer-plate 157 will be held in inward position, and the lever 123 in the "reverse" position. When the safety mechanism is to be reset, the levers 167 and 169 are manually flexed inward to the position shown in Fig. 7, the lever 123 remaining in "reverse" position until swung manually to "neutral" or "ahead" position, or until the travel of the carriage has caused roller 131 to contact with tappet 141 and stop the travel of the carriage.

A similar safety reversing arrangement is arranged upon the rear of the carriage, corresponding elements being marked with

primed reference numerals similar to those used for the corresponding elements on the safety stop device previously described. The operating lever 123' at this end of the carriage operates a lever arm 181, and through a connecting rod 182 to exert a pull on an arm 183 fixed to the shaft 119, so that the latter shaft may be operated by the operating device 123' to control the controller in the same manner as is effected by the lever 123. When the carriage is travelling in the reverse direction, and the buffer 157' is struck by an obstruction, the safety reversing mechanism at this end of the carriage operates first to throw the controlling levers to the position to cause the carriage to travel in a reverse direction which corresponds to the forward direction. The carriage will then continue to travel in a forward direction until either the lever 123 is pulled manually to the neutral position, or else the roller 125 contacts with abutment 126 which would overcome the safety mechanism and reverse the direction of travel of the carriage; however, as soon as roller 125 has left abutment 126 on the rearward travel of the carriage, the safety stop would again reverse the carriage travel and cause the same action to take place.

The construction and arrangement of the tappet 138 is such as to provide for overrun or coasting of the carriage after current is shut off from the motor, and at the same time not to interfere with the operation of the safety reversing mechanism when the carriage has been started on its forward travel, in other words, so as to permit the buffer-plate to move the controller operating mechanism to the reverse position, as shown in Fig. 8.

At its forward portion the carriage is provided with a transverse leveller or striker member, preferably in the form of a plate 184, pivotally supported, as at 185, on a transverse bar member 186 fixed in the upper ends of brackets 187 carried by the forward ends of retainer-plates 188, to be described hereinafter. The plate 184 may, if desired, have a serrated or notched lower edge, as at 189. The plate at its ends is provided with stop arms 190 having adjusting bolts 191 adapted to engage with stops 192, preferably integral with said brackets 187. The arms 190 are so located, and the bolts so adjusted, that the plate 184 is inclined downward and rearward from its pivot relative to the forward direction of travel of the carriage. During forward movement of the carriage, the plate 184, because of its pivotal mounting, may swing upward and ride freely over the sand in the mold, but during the rearward movement of the carriage, said plate remains in its lowermost position, as shown in Figs. 2, 4 and 6, and serves to level or strike the sand which has been rammed. Beyond the plate 184 is a sand-distributing and levelling member, preferably in the form of a rigid plate 193

located in advance of the rammers and extending transversely of the carriage, said plate being supported at its ends preferably by integral brackets 194 rigidly connected by bolts 195 to the front members 21 of the carriage. The bolts are preferably adjustably arranged in slots 196 in said member 21, in order that the plate 193 may be adjusted vertically to regulate its height with reference to the mold to be rammed. The plate 193 is formed with oppositely and rearwardly inclined members 197, which are also inclined from their upper edge toward their forward lower edge, the arrangement being such that during the forward movement of the carriage, said plate acts as a plow or scraper to distribute the sand evenly from the center of the mold toward its side edges, and to bring the sand to the desired level and thickness to be properly rammed by the rammers.

In rear of the rammers is arranged a transverse frame member 198, supported at its ends by angle-brackets 199 bolted to the said retaining members 188 heretofore mentioned; and supported on the member 198 are a plurality of plows 200, there being preferably one of said plows arranged behind each of the ramming feet heretofore described. These plows consist, preferably, of rearwardly inclined plates 201, whereby said plows are V-shaped in plan view. The upper edges of the side members 201 are provided with lateral horizontal flanges 202 adapted to receive clamping bolts 203 passing through longitudinal slots 204 in the member 198, whereby the plows are secured to said member and are capable of adjustment longitudinally of the latter to bring them into proper position relative to the ramming feet. These plows 200 serve to level and distribute the sand after the rammers have passed over the same to perform a ramming operation, so that the sand will be in proper condition to be rammed again when the carriage makes the return movement of its reciprocation.

The carriage is provided at its lower side portions with the sand retainer plates 188, heretofore mentioned, which are adapted to travel on or adjacent the side edges of the flask to act as guards to prevent the sand being thrown outward by the action of the rammers and of the sand-levelling device described. Each of the said plates is arranged and mounted so as to yieldingly rest on the flask, and for this purpose is provided on its outer face and at each end with a hanger 205, preferably consisting of an angle-iron, as shown in Figs. 4, 10 and 11 of the drawings. Secured to this angle-iron is an angle-bracket 206, one portion of which is arranged in a horizontal plane, as at 207, provided with spaced apertures 208, 209. Below the angle piece 206, the plate 188 is provided with an outwardly projecting lug 210 having a guide aperture 211. The sand-retainer or guard

plate is supported at each of its ends by a headed bolt 212 threaded in the said opening 209 and passing through an opening 213 in the horizontal flange of the longitudinal frame member 22, the head of the bolt resting 70 on the said member 22, and the lower end of the bolt carrying a lock-nut 214 located beneath the bracket member 207. Passing through the openings 208 and 211 is a vertical guide pin 215, receiving at its upper 75 end a cotter-pin 216 located above the member 22, and at its lower end receiving a cotter-pin 217 located beneath the lug 210, the intermediate portion of said pin 215 passing through openings in the flange of the lower longitudinal frame member 23, as will be clear from Figs. 4, 6 and 10 of the drawings. By this arrangement the plate 188 is guided in its vertical movement and is maintained in a substantially vertical plane by the said 80 bolts 212 and pins 215. The forward lower edges of the plates 188 are inclined upward, as at 188^a, so that the said plates may ride up onto the side edges of a flask, and the support afforded by the bolts 212 and pin 215 will permit 85 said plate to adjust its level to that of the upper edge of the mold. The plates 188, as shown, are adapted to cooperate with a mold of substantially the same width as the carriage, but, if desired, they may be employed 90 to support supplemental guard or retainer-plates 218, which may be supported on the inner faces of the plates 188 by means of angle-brackets 219 bolted, or otherwise secured, to the inner faces of the said plates 188. 95 (See Figs. 3 and 10 of the drawings.) When the supplemental inner plates are used, they may serve, if desired, as the supports for the member 198, as shown in Fig. 10. The supplemental plates 218 are adapted to cooperate 100 with flasks narrower than those approximating the width of the carriage, as above stated with respect to the plates 188.

Provision is also made whereby the location of the outer pair of rammer feet may be 110 adjusted for either narrow or wide molds. This is accomplished by making each of the crank-pins 31 long enough to provide for lateral adjustment of the bearing 33 thereon, so that the connecting rod 34 and the rammer 115 supported thereby may be adjusted transversely of the machine. When the connecting bar is adjusted to this innermost position on the crank, that is, for the ramming of a narrower mold, a split spacing collar 220 is 120 arranged on the crank-pin between the outer face member of the crank and the bearing member, whereas when a broader mold is to be rammed, the bearing 33 is adjusted in the outer position, as shown in Fig. 3, and the collar 220 is placed between said bearing member and the inner face member of the crank. It will be understood that in making the adjustments mentioned, the distance rod or member 41 is correspondingly adjusted 125 130

lengthwise of the shaft 42 and maintained in proper position by the collars 41^b.

What I claim and desire to secure by Letters Patent of the United States is:—

- 5 1. A mold-ramming machine comprising an elevated trackway, a carriage movable along the trackway, ramming means on the carriage, propelling means adapted to reciprocate the carriage, means driven from said propelling means for operating said ramming means, a controller on the carriage and having forward, neutral and reverse controlling effects on said propelling means, and means on the carriage and trackway cooperable to 10 actuate the controller to cause any of said effects.
2. A mold-ramming machine comprising an elevated trackway, a carriage movable along the trackway, ramming means on the carriage, reversible motor-propelling means on the carriage for reciprocating the same on the trackway, a controller having forward, means driven from said motor propelling means for operating said ramming means, neutral and reverse effects on said motor propelling means, manually operable means on the carriage for moving said controller to produce any one of said effects, and means on the trackway and carriage cooperable to 15 actuate automatically the controller to produce said effects.
3. A mold-ramming machine comprising an elevated trackway, a carriage movable along the trackway, ramming means on the carriage, motor propelling means for reciprocating the carriage, means driven from said motor propelling means for operating said ramming means, a controller for said motor propelling means and having forward, neutral and reverse controlling positions for the motor, and manually operable means on the carriage for actuating the controller to any of said positions.
4. A mold-ramming machine comprising an elevated trackway, a carriage movable along the trackway, ramming means on the carriage, motor propelling means for reciprocating the carriage, means driven from said motor propelling means for operating said ramming means, a controller for said motor propelling means and having forward, neutral and reverse controlling positions for the motor, manually operable means on the carriage for actuating the controller, and automatically operable means actuated by engagement with an obstruction in the path of movement of the carriage whereby said controller is actuated to reverse the travel of the carriage.
5. A mold-ramming machine comprising an elevated trackway, a carriage movable along the trackway, ramming means on the carriage, motor propelling means for reciprocating the carriage, means driven from said motor propelling means for operating said ramming means, a controller for said motor propelling means and having forward, neutral and reverse controlling positions for the motor, manually operable means on the carriage for actuating the controller, and automatically operable means actuated by engagement with an obstruction in the path of movement of the carriage whereby said controller is actuated to reverse the travel of the carriage.
6. A mold-ramming machine comprising an elevated trackway, a carriage on the trackway, ramming means on the carriage, a reversible propelling means for reciprocating the carriage along the trackway, means driven from said propelling means for operating said ramming means, a controller for said propelling means constructed to produce forward, neutral and reverse effects thereon, manually operable means on the carriage for actuating said controller, a rocking member on the carriage operatively connected to said controller and having projections, and means on the trackway adapted to be engaged by said projections to actuate the controller.
7. A mold-ramming machine comprising an elevated trackway, a carriage movable along the trackway, ramming means on the carriage, means for driving the carriage, means driven from said driving means for operating said ramming means, a controller for reversing the driving means, a safety mechanism adapted to be actuated automatically by engagement with an obstruction to operate the controller, said means including a spring normally tending to operate the controller to reverse said driving means, and means normally preventing operation of the controller by the spring.
8. A mold-ramming machine comprising an elevated trackway, a carriage on the trackway, ramming means on the carriage, means for reciprocating the carriage and comprising a reversible motor on the carriage, means driven from said motor for operating said ramming means, a controller for the motor constructed and adapted to produce forward, neutral and reverse effects on the motor and including a rotatable member having a gear, a gear segment cooperable with said gear, and manually operable means on the carriage for swinging said gear segment to thereby operate said controller.
9. A mold-ramming machine comprising an elevated trackway, a carriage on the trackway, ramming means on the carriage, means for reciprocating the carriage and comprising a reversible motor on the carriage, means driven from said motor for operating said ramming means, a controller for the motor constructed and adapted to produce forward, neutral and reverse effects on the motor and including a rotatable member having a gear, a gear segment cooperable with said gear,

and means on the trackway and the carriage cooperable during the movement of the latter to swing said segment to actuate the controller.

- 5 10. A mold-ramming machine comprising an elevated trackway, a carriage on the trackway, ramming means on the carriage, means for reciprocating the carriage and comprising a reversible motor on the carriage, means 10 driven from said motor for operating said ramming means, a controller for the motor constructed and adapted to be moved to positions to produce forward, neutral and reverse effects on the motor and including a rotatable member having a gear, a gear segment cooperable with said gear, and means on the trackway and the carriage cooperable during the movement of the latter to swing said segment to actuate the controller to neutral, reverse and neutral positions in sequence.
- 15 11. A mold-ramming machine comprising an elevated trackway, a carriage on the trackway, ramming means on the carriage, means for reciprocating the carriage and comprising a reversible motor on the carriage, means 20 driven from said motor for operating said ramming means, a controller for the motor constructed and adapted to be moved to positions to produce forward, neutral and reverse effects on the motor and including a rotatable member having a gear, a gear segment 25 cooperable with said gear, means on the trackway and the carriage cooperable during the movement of the latter to swing said segment to actuate the controller, and reversing mechanism operable upon engagement of the carriage with an obstruction to 30 actuate said controller to reverse the movement of said carriage.
- 35 12. A mold-ramming machine comprising an elevated trackway, a carriage on the trackway, ramming means on the carriage, means for reciprocating the carriage and comprising a reversible motor on the carriage, means 40 driven from said motor for operating said ramming means, a controller for the motor constructed and adapted to be moved to positions to produce forward, neutral and reverse effects on the motor and including a rotatable member having a gear, a gear segment 45 cooperable with said gear, and means on the trackway and the carriage cooperable during the movement of the latter to swing said segment to actuate the controller to move the 50 same to reverse position.

- 55 13. A mold-ramming machine comprising an elevated trackway, a carriage on the trackway, ramming means on the carriage, means for reciprocating the carriage and comprising a reversible motor, means driven from said motor for operating said ramming means, a controller for the motor constructed and adapted to be moved to positions to produce forward, neutral and reverse effects on the motor, means operable by travel of the 60 65

carriage to move said controller to neutral and reverse positions in sequence, and safety means on the carriage movable by engagement with an obstruction to move said controller to reverse position.

70 14. A mold-ramming machine comprising an elevated trackway, a carriage on the trackway, ramming means on the carriage, means for reciprocating the carriage and comprising a reversible motor, means driven from 75 said motor for operating said ramming means, a controller for the motor constructed and adapted to be moved to positions to produce forward, neutral and reverse effects on the motor, means operable by travel of the 80 carriage to move said controller to neutral and reverse positions in sequence, and safety means on the carriage movable by engagement with an obstruction during either direction of travel of the carriage to actuate said controller to reverse the travel of the carriage.

85 15. A mold-ramming machine comprising an elevated trackway, a carriage movable along the trackway, ramming means on the 90 carriage, propelling means for reciprocating the carriage, means driven from said propelling means for operating said ramming means, a controller for said propelling means and having forward, neutral and reverse positions, buffer means on the carriage operable by engagement with an obstruction to move the controller to reverse position, and means engageable by the controller on return movement of the carriage for moving the controller to neutral position to stop the carriage.

95 16. A mold-ramming machine comprising an elevated trackway, a carriage movable along the trackway, ramming means on the carriage, propelling means for reciprocating 105 the carriage, means driven from said propelling means for operating said ramming means, a controller for said propelling means and having forward, neutral and reverse positions, buffer means on the carriage operable 110 by engagement with an obstruction to move the controller to reverse position, and means engageable by the controller on return movement of the carriage for moving the controller to neutral position to stop the carriage, 115 said last-named means including a tappet member rigid on the return movement of the carriage, but yieldable on the forward movement of the carriage.

120 17. A mold-ramming machine comprising an elevated trackway, a carriage movable along the trackway, ramming means on the carriage, means for reciprocating the carriage, means driven from said last mentioned means for operating said ramming means, 125 and means to reverse automatically the travel of the carriage during either movement of a reciprocation.

130 18. A mold-ramming machine comprising an elevated trackway, a carriage movable

along the trackway, ramming means on the carriage, a reversible motor for reciprocating the carriage, means driven from said motor for operating said ramming means, a controller for the motor, and means to operate the controller to reverse automatically the travel of the carriage during either movement of a reciprocation.

19. A mold-ramming machine comprising an elevated trackway, a carriage movable along the trackway, ramming means on the carriage, a reversible motor for reciprocating the carriage, means driven from said motor for operating said ramming means, a controller for the motor, and safety means adapted to be operated by engagement with an obstruction in the path of the carriage to operate said controller to reverse the travel of the carriage during either movement of a reciprocation.

20. A mold-ramming machine comprising an elevated trackway, a carriage movable along the trackway, ramming means on the carriage, means for driving the carriage, means driven from said last mentioned means for operating said ramming means, a controller for the driving means, a safety mechanism adapted to be operated by engagement with an obstruction to operate the controller to reverse said driving means, said means including a spring normally tending to operate the controller, and a snap action normally preventing operation of the controller by the spring.

21. A mold-ramming machine comprising an elevated trackway, a carriage movable along the trackway, ramming means on the carriage, means for driving the carriage, means driven from said last mentioned means for operating said ramming means, a controller for said driving means, a safety mechanism adapted to be operated by engagement with an obstruction to operate the controller to reverse said driving means, said safety mechanism including a spring normally tending to operate said mechanism to actuate the controller, a snap action normally holding said mechanism against operation, and means actuated by engagement with an obstruction to release said snap action.

22. A mold-ramming machine comprising an elevated trackway, a carriage movable along the trackway, ramming means on the carriage, means for driving the carriage, means driven from said last mentioned means for operating said ramming means, a controller for said driving means, a safety mechanism adapted to be operated by engagement with an obstruction to actuate the controller to reverse said driving means, said safety mechanism including a spring normally tending to actuate the controller, jointed levers adapted to take a position to hold the said spring against operation of the controller, a buffer adapted to be engaged by

an obstruction, and a connection between the buffer and said levers whereby the latter are moved to a position to release the spring when the buffer is engaged by an obstruction.

23. A mold-ramming machine comprising an elevated trackway, a carriage movable along the trackway, ramming means on the carriage, means for driving the carriage, means driven from said last mentioned means for operating said ramming means, a controller for said driving means, a manually operable shaft on the carriage, and means for connecting said shaft and the controller whereby the latter may be manually operated.

24. A mold-ramming machine comprising an elevated trackway, a carriage movable along the trackway, ramming means on the carriage, means for driving the carriage, means driven from said last mentioned means for operating said ramming means, a controller for said driving means, a manually operable shaft on the carriage, means for connecting the shaft and the controller whereby the latter may be operated, a spring normally tending to move said shaft to operate the controller, a snap action restraining said spring, and a buffer-element on the carriage for operating the snap action to release the spring.

25. A mold-ramming machine comprising an elevated trackway, a carriage movable along the trackway, ramming means on the carriage, means for driving the carriage, means driven from said last mentioned means for operating said ramming means, a controller for said driving means, a manually operable shaft on the carriage, means for connecting the shaft and the controller whereby the latter may be operated, a spring normally tending to move said shaft to operate the controller, a snap action restraining said spring, a buffer-element on the carriage for operating the snap action to release the spring, and means whereby said shaft is independently operable manually or by said spring.

26. A mold-ramming machine comprising a carriage adapted to travel across a mold, means for propelling the carriage, ramming means on the carriage, means driven from said propelling means for operating said ramming means, guard-members yieldingly supported at the sides of the carriage, and supplemental guard-members supported by said first-named guard-members.

27. A mold-ramming machine comprising a carriage adapted to travel across a mold, means for propelling the carriage, ramming means on the carriage, means driven from said propelling means for operating said ramming means, guard-members yieldingly supported at the sides of the carriage, brackets on the inner faces of said guard-members, and supplemental guard-members supported by said brackets.

28. A mold-ramming machine comprising

- a carriage adapted to travel across a mold, means for propelling the carriage, a plurality of ramming feet on the carriage and arranged transversely thereof, and a sand-leveling and distributing member arranged in rear of each of said feet, each of said members comprising plates inclined outwardly and rearwardly relative to one direction of travel of the carriage.
29. A mold-ramming machine comprising an elevated trackway, a carriage movable along the trackway and adapted to travel across a mold, a crank shaft arranged transversely of the carriage and having a plurality of cranks, connecting members suspended from the cranks and supporting ramming feet, and means whereby said connecting members are adjustable transversely of the carriage.
30. A mold-ramming machine comprising an elevated trackway, a carriage movable along the trackway and adapted to travel across a mold, a crank shaft arranged transversely of the carriage and having a plurality of cranks, connecting members suspended from the cranks and supporting ramming feet, and means whereby said connecting members are adjustable transversely of the carriage, said means comprising spacing collars for locating the connecting member on the crank lengthwise of the latter.
31. A mold-ramming machine comprising an elevated trackway, a carriage reciprocable along the trackway, means for reciprocating the carriage, a plurality of ramming elements arranged in line transversely of the carriage, a sand-distributing member arranged in advance of the rammers to distribute the sand on one movement of a reciprocation, and levelling means located in rear of the rammers to level and distribute the rammed sand on the same movement of reciprocation.
32. A mold-ramming machine comprising a carriage adapted to reciprocate across a mold, means for reciprocating the carriage, a plurality of ramming feet on the carriage and arranged transversely thereof, sand-leveelling means in advance of the ramming feet on one movement of reciprocation, and sand-leveling and distributing members in rear of said ramming feet relative to said one movement of reciprocation and operating to level and distribute the rammed sand whereby to present substantially level sand to the rammers on the other movement of reciprocation of the carriage.
33. A mold-ramming machine comprising an elevated trackway, a carriage movable along the trackway, ramming means on the carriage, propelling means for reciprocating the carriage, means driven from said propelling means for operating said ramming means, a controller for said propelling means and having forward, neutral and reverse positions, manual means for moving the controller to forward position to cause the propelling means to drive the carriage forward, means on the trackway to move the controller to reverse position to cause the propelling means to drive the carriage rearward, and means on the trackway near the end of said rearward travel to move the controller to neutral to stop the propelling means for the carriage.
34. A mold-ramming machine comprising an elevated trackway, a carriage movable along the trackway, ramming means on the carriage, propelling means for reciprocating the carriage, means driven from said propelling means for operating said ramming means, a controller for said propelling means and having forward, neutral and reverse positions, manual means for moving the controller to forward position to cause the propelling means to drive the carriage forward, means on the trackway to move the controller to neutral position, means on the trackway acting after the controller has been moved to neutral position to move the controller to reverse position to cause the propelling means to drive the carriage rearward, and means on the trackway near the end of said rearward travel to move the controller to neutral to stop the propelling means for the carriage.
35. A mold-ramming machine comprising an elevated trackway, a carriage movable along the trackway, ramming means on the carriage, propelling means for reciprocating the carriage, means driven from said propelling means for operating said ramming means, a controller for said propelling means and having forward, neutral and reverse positions, manual means for moving the controller to forward position to cause the propelling means to drive the carriage forward, means on the trackway to move the controller to reverse position to cause the propelling means to drive the carriage rearward, means on the trackway near the end of said rearward travel to move the controller to neutral to stop the propelling means for the carriage, and safety buffer means on the carriage and operable at any point in forward travel of the carriage to move the controller to reverse position to reverse travel of the carriage.

In witness whereof, I have hereunto subscribed my name.

SHERWOOD C. BLISS.
